UNITED STATES PATENT OFFICE

112,201

DESIGN FOR AN AUTOMOBILE BUMPER

Peter N. Madsen, Detroit, Mich.

Application July 25, 1938, Serial No. 78,698

Term of patent 3½ years

To all whom it may concern:

Be it known that I, Peter N. Madsen, a citizen of the United States, residing at Detroit, county of Wayne, in the State of Michigan, have invented a new, original, and ornamental Design for an Automobile Bumper, of which the following is a specification, reference being made to the accompanying drawing, forming part thereof.

Fig. 1 is a front view of an automobile bumper showing my new design.

Fig. 2 is a top plan view thereof.

Fig. 3 is a side elevation thereof.

Fig. 4 is a rear perspective view thereof.

I claim:

The ornamental design for an automobile bumper, as shown.

PETER N. MADSEN.
